US00D945803S

(12) **United States Design Patent** (10) Patent No.: **US D945,803 S**
(45) Date of Patent: **** Mar. 15, 2022**

(54) **DISPLAY STAND**

- (71) Applicant: **Apple Inc.**, Cupertino, CA (US)
- (72) Inventors: **Sheng Yang**, Mountain View, CA (US); **Olivia M. Ching**, Mountain View, CA (US); **Chien Tsun Chen**, Taipei (TW); **Eric Weijia Wang**, Newark, CA (US); **Ricardo A. Mariano**, Hayward, CA (US); **Allison Inouye**, San Francisco, CA (US); **Kristy Judy Hsu**, San Jose, CA (US); **Po Huang**, San Jose, CA (US); **Jean-Marc Gady**, Los Altos, CA (US); **Peter Russell-Clarke**, San Francisco, CA (US); **Daniele De Iuliis**, San Francisco, CA (US); **Jeremy Bataillou**, San Francisco, CA (US); **Markus Diebel**, San Francisco, CA (US); **Rico Zörkendorfer**, San Francisco, CA (US); **Molly Anderson**, San Francisco, CA (US); **Shota Aoyagi**, San Francisco, CA (US); **Jody Akana**, San Francisco, CA (US)
- (73) Assignee: **Apple Inc.**, Cupertino, CA (US)

(**) Term: **15 Years**

(21) Appl. No.: **29/807,507**

(22) Filed: **Sep. 13, 2021**

Related U.S. Application Data

(63) Continuation of application No. 29/758,623, filed on Nov. 17, 2020, now Pat. No. Des. 930,414, which is (Continued)

“Freedom Series,” Takachiho Koheki Co., Ltd., cited in Office Action dated Apr. 6, 2016, in Japanese Patent Application No. 2015-009263, Apple Inc., filed Apr. 24, 2015.

Primary Examiner — Kelley A Donnelly

(74) Attorney, Agent, or Firm — Sterne, Kessler, Goldstein & Fox P.L.L.C.

(57) **CLAIM**

The ornamental design for a display stand, as shown and described.

DESCRIPTION

FIG. 1 is a top front perspective view of a display stand showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top front perspective view thereof showing the claimed design in an environment in which it may be used; and,

FIG. 9 is a bottom rear perspective view thereof.

The dashed broken lines in the figures show portions of the display stand and environment that form no part of the claimed design.

1 Claim, 7 Drawing Sheets

Related U.S. Application Data

a continuation of application No. 29/743,203, filed on Jul. 20, 2020, now Pat. No. Des. 904,091, which is a continuation of application No. 29/695,817, filed on Jun. 21, 2019, now Pat. No. Des. 893,926.
